H. A. DOUGLAS.
CIRCUIT CONNECTOR.
APPLICATION FILED MAR. 27, 1916.

1,220,139.

Patented Mar. 20, 1917.

Inventor:
Harry A. Douglas
By G. C. Gray, Atty.

UNITED STATES PATENT OFFICE.

HARRY A. DOUGLAS, OF BRONSON, MICHIGAN, ASSIGNOR TO DOUGLAS & RUDD MFG. CO., OF BRONSON, MICHIGAN, A CORPORATION OF MICHIGAN.

CIRCUIT-CONNECTOR.

1,220,139.

Specification of Letters Patent. Patented Mar. 20, 1917.

Application filed March 27, 1916. Serial No. 88,865.

To all whom it may concern:

Be it known that I, HARRY A. DOUGLAS, citizen of the United States, residing at Bronson, in the county of Branch and State of Michigan, have invented a certain new and useful Improvement in Circuit-Connectors, of which the following is a full, clear, concise, and exact description, reference being had to the accompanying drawings, forming a part of this specification.

My invention relates to circuit closing switches, extenders or connectors and has for its object the provision of improved means whereby two component parts of the device may have two relative adjustments while in assembly, one for closing the circuit and the other for opening the circuit. A switch made in accordance with my invention is inclusive of two contact carriers, a shell with in which one of these contact carriers is disposed, this shell and the other contact carrier having supplemental coupling formations whereby this latter contact carrier may be placed in an inner and outer position while coupled with the shell, the contacts upon the carriers being so positioned that they are connected when the contact carrier having coupling engagement with the shell is in its inner position and are disconnected when this contact carrier is in its outer position, an abutment having a cup-shaped portion engaging this carrier and surrounding the contact upon this carrier that is supplemental to the contiguous contact upon the intermediate carrier, and a spring maintaining pressure of the abutment against the end contact carrier engaged by the abutment.

I will explain my invention more fully by reference to the accompanying drawing showing the preferred embodiment thereof and in which Figure 1 is a view in elevation of a tubular shell entering into the construction; Fig. 2 is a view showing the tubular shell in section, the plug and lamp in elevation, and a contact carrier within the shell in section, the plug and lamp being in circuit; and Fig. 3 is a view showing the plug in its outer position to exclude the lamp from circuit, the shell, the contact carrier, and the follower being shown in section.

Like parts are indicated by similar characters of reference throughout the different figures.

The structure illustrated is inclusive of a metallic shell 1 inclosing an intermediate

contact carrier 2 of insulating material, this contact carrier being centrally disposed when the shell is employed and constructed to couple a lamp 3 and a plug 4 or other contact carriers, though the invention is not to be limited to this form of switch. When constructed for this purpose the shell desirably has bayonet slots at each end, the bayonet slots 5 at one end being adapted to receive bayonet pins 6 upon the contact carrying portion or base of the lamp, the lamp desirably having only one relative position with respect to the shell when the lamp and shell are coupled. The bayonet slots at the other end of the shell are provided each with two seats 7 and 8 (constituting coupling formations) upon the shell 1 that are separated longitudinally of the shell whereby the bayonet pins 9 (also constituting coupling formations) may be interengaged with the shell at different places longitudinally thereof for the purpose of holding the plug 4 in assembly with the shell while the plug is either in its inner or outer position, the arrangement being such that when the plug is in its innermost position it will be included in circuit and when it is in its outermost position it will be excluded from circuit. While the plug illustrated merely serves as a contact terminal carrier for the conducting wires 10 and 11 leading thereto from a suitable source of current, the invention is not to be limited to a plug that is employed for this purpose as the invention contemplates the use of such a plug as a contact carrier irrespective of the circuit portions with which the contacts upon the plug are connected.

An abutment 12 is outwardly pressed by a coiled spring 13 the outer end of which is attached to the cup-shaped abutment 12 so as to be mechanically coupled therewith while the inner end of the spring is received within the annular recess 14 provided therefor in the contact carrier 2, the contact carrier and the inner end of the spring being also coupled together. The abutment 12 is desirably annular and is of a diameter materially less than the inner diameter of the shell 1 whereby such abutment is capable of universal movement within a suitable range to enable it properly to perform its function.

Assuming that the lamp is in place the ultimate terminals thereof in the device disclosed are the plunger contact 15 substantially co-axial with the abutment 12 and

the metallic shell 1, the lamp filament terminals 16, 17 upon the base of the lamp being respectively in electrical connection with the shell 1 and contact 15, the contact 15 being electrically connected with the contact 18 that engages the contact 17 when the lamp is in place. A spring 19 presses the contacts 15 and 18 apart and enables the contact 18 to hold the bayonet pins 6 in place within the bayonet slots 5. The contacts 15 and 18 that are carried by the contact carrier 2 are substantially co-axial with the shell 1. The coiled spring 13 is also co-axial with the shell and surrounds the contact 15 and bears upon the element 12 that also surrounds said contact and the contact 20 to engage directly the carrier of the latter contact. The contact 15, however, has to be separated from the contact 20 upon the plug 4 when the lamp or any other circuit portion connected with the contact 15 is to be excluded from circuit. The ring 12 constitutes a following abutment since the spring 13 is sufficiently long to enable the ring 12 to hold the plug 4 with the bayonet pins 9 in either pairs of seats 7 or 8. When these bayonet pins 9 are in the seats 8 the plug 4 and shell 1 are still in mechanical assembly but the circuit connection is broken since the contact 15 has a limit of outward movement that permits this contact to follow the plug 4 in the movement of the latter from the seats 7 to the seats 8 for a very short distance and to cease following before the pins 9 reach the seats 8 whereby the contact carriers 2 and 4 are maintained in mechanical assembly while electrically separate, when the carrier 4 is in its outer position and are both mechanically and electrically assembled when the carrier 4 is in its inner position since the carrier 4 has a metallic sheath 21 that is electrically in contact with the metallic shell 1. The switch illustrated is a single pole connector in which the contact 15 is included in circuit by way of another contact 18 symmetrically positioned with respect to the contact 15 but it is to be understood that the invention is not to be limited to single pole connectors nor to the manner in which the contacts carried by the contact carrier 2 are included in circuit at the end of the shell 1 opposite to that where the plug 4 is received. The floating follower 12 is desirably cup-shaped, the rim of the cup being larger than the body of the cup, the reduced

portion of the cup being surrounded by the spring 13. By means of the universal mounting for the follower 12 this follower will have universal engagement with the insulating portion of the plug 4 and will not warp or tilt the plug. The follower, by having ample clearance surrounding it and between it and the shell and because of the manner of its mounting, will not bind as it moves longitudinally of the shell but will be free to move universally about within the shell to a sufficient extent in order that it may rest flat upon the plug at all times and be free of binding engagement with the shell 1.

While I have herein shown and particularly described the preferred embodiment of my invention I do not wish to be limited to the precise details of construction shown as changes may readily be made without departing from the spirit of my invention. Having thus described my invention I claim as new and desire to secure by Letters Patent the following:

A switch including a shell having bayonet slots at the ends thereof, the bayonet slot at one end having two bayonet pin engaging seats spaced apart longitudinally of the shell; contact carriers at the ends of the shell and having bayonet pins engageable with the seats in the bayonet slots; an intermediate contact carrier within the shell and carrying contacts upon the ends thereof which are engageable with the contacts upon the aforesaid contact carriers, the contact element upon the end of the intermediate contact carrier that is adjacent that end of the shell whose bayonet slot has two seats being substantially co-axial with the shell; an abutment surrounding the latter contact and having a cup-shaped portion engaging the carrier at the latter end of the shell and surrounding the contact upon this carrier that is complementary to the contiguous contact upon the intermediate carrier; and a spring maintaining pressure of the abutment against the end contact carrier engaged by the abutment.

In witness whereof, I hereunto subscribe my name this 16th day of March A. D., 1916.

HARRY A. DOUGLAS.
